CLAIM

The ornamental design for a surgeon display screen with a graphical user interface having a spent staple icon as shown and described.

DESCRIPTION

FIG. 1 is a front view of a surgeon display screen showing a spent staple icon presented with environmental broken line subject matter; and,

FIG. 2 is an enlarged view of the spent staple icon with broken line subject matter removed for clarity of illustration. The broken lines showing the display screen form no part of the claimed design. The remaining broken lines showing remaining portions of the graphical user interface form no part of the claimed design.
